UNITED STATES PATENT OFFICE.

CLARENCE E. LOMAX, OF CHICAGO, ILLINOIS, ASSIGNOR, BY MESNE ASSIGNMENTS, TO
AUTOMATIC ELECTRIC INC., OF CHICAGO, ILLINOIS, A CORPORATION OF DELAWARE.

AUTOMATIC TELEPHONE SYSTEM.

Application filed May 14, 1921. Serial No. 469,414.

The present invention relates in general to automatic telephone systems, but more especially to modern systems of the so-called "two wire" type, in which the automatic switches are controlled over the two sides of a calling line in series; and the object, broadly stated, is to improve the circuits of the switching mechanism at the exchange with a view principally to substituting positive circuit arrangements for performing certain necessary functions in place of the circuit arrangements ordinarily used heretofore which depend on relays which are slow to deenergize.

15 The idea which forms the main feature of the invention may be best understood by a comparison of the circuit arrangement commonly used to perform a certain function in a first selector switch, for example, 20 with the arrangement herein proposed for performing the same function. According to the present practice the selector switch is provided with a line relay for controlling the operation of the switch and a slow acting release relay for controlling the release. The latter relay is energized by the line relay and due to its slow releasing characteristic it holds up during momentary deenergizations of the line relay while the switch 25 is being operated, holds the release magnet circuit open, and maintains ground on the release trunk to provide a holding circuit for the preceding switch or switches. As soon as a second selector trunk line is selected the 30 switching relay pulls up, disconnects the incoming line conductors from the line relay and extends them to the line relay of the second selector, and connects the incoming release trunk by way of the test wiper to the 35 outgoing release trunk extending to the second selector. When the line relay of the first selector is disconnected it immediately falls back and opens the circuit of the slow acting release relay, but this relay, being 40 slow to deenergize, does not fall back at once but maintains the release trunk grounded until ground is fed back from the second selector. This occurs when the line and release relays of the second selector pull up 45 responsive to the extension of the line conductors and ordinarily requires only a small fraction of a second for its accomplishment, but until ground is actually fed back the entire connection depends on the time element 50 of the first selector release relay in de-

energizing. If the grounding of the release trunk is delayed for any reason at the second selector, or if any one of the trunk conductors to the second selector, either a line conductor or the release trunk conductor, is 55 open ground will not be fed back in time and as soon as the release relay falls back the connection is released.

It will be obvious that there is a critical time in the operation of the above described 60 circuit arrangement when any one of numerous troubles or imperfections will cause it to fail, and the present invention is designed to eliminate this critical period entirely. According to the scheme proposed herein, 65 and considering a first selector switch as in the foregoing, the release relay is provided with a low resistance winding which is normally short circuited and which is connected to the release trunk to provide a holding 70 ground for the preceding switch while the first selector is operating. This short circuited winding, it should be stated, renders the relay slow to release so that it will not fall back during impulses. When a second 75 selector trunk is selected and the switching relay pulls up the same operations as described in the case of the ordinary first selector take place, and in addition the short circuit is removed from the low resistance 80 winding of the release relay. This winding then supplies ground to the release trunk and the release relay remains locked up. In due course the line and release relays of the 85 second selector pull up and the latter places ground on the extended release trunk, thereby again short circuiting the release relay in the first selector which is thus finally deenergized. It will be seen that this arrangement entirely eliminates the time element in 90 switching through to a selected trunk line. In case a trunk conductor should be open, of course, ground will not be fed back and instead of being released the connection will remain locked up. This is a desirable result 95 for it makes it possible to immediately locate open trunks. An alarm circuit is provided to notify the switchboard attendant whenever a connection becomes locked due to failure of a switch to receive a ground from 100 a succeeding switch, and the attendant can at once correct the trouble, or busy the trunk, while at the same time he can talk to the calling subscriber and have him try the 105 number again.

The broad idea outlined above may be applied to other types of switches, including the primary line switches, and several modifications are shown and described herein. It should be stated also that the principle involved is especially valuable when secondary line switches are employed and on this account such switches are shown and will be described with particular reference to the improved operation secured.

A further feature which is closely related to the foregoing has to do with an improved type of repeater which is so arranged that in case the outgoing trunk line associated therewith is open any call received at the repeater will be locked up and an alarm will be sounded to notify the attendant.

Still other features of the invention relate to an improved control circuit for the line relay of a selector or connector switch, and to an improved method of providing for the "change over" in a selector switch. The foregoing and other features not now specifically mentioned will be described hereinafter with reference to the accompanying drawings, in which there is illustrated by means of the usual circuit diagram sufficient of the apparatus in a telephone system embodying the invention to enable the same to be explained and understood.

To facilitate the explanation of the various features a multi-office telephone system has been assumed, and the drawings when laid out in order, with the corresponding lines at the ends thereof in alignment, show the apparatus which is required to extend a connection from a calling station A, Fig. 1, in one of the offices or exchanges of the system to a called station A', Fig. 4, in another office or exchange of the system. This apparatus comprises the primary line switch P and the secondary line switch S, Fig. 1, the first selector D, and the outgoing secondary rotary line switch S², Fig. 2, and the repeater R, Fig. 3, all of which are located in the originating exchange, together with the incoming selector E, Fig. 3, and the connector H, Fig. 4, which are located in the second exchange.

All of the switches, except for the novel circuit improvements introduced, are of well known construction and function and on this account will not be described in detail as to their mechanical operation. This applies also to the trunking arrangements, and to the equipment at the subscribers' stations. Further details may be had if desired by referring to the book entitled "Automatic Telephone Practice" by Harry E. Hershey, third edition.

It may be stated, however, that the selector and connector switches in all offices are of the Strowger vertical and rotary type. In the originating exchange calling lines are extended to first selector switches by means of primary and secondary line switches of

the Keith or plunger pre-selecting type. In the second office or exchange, in which the called line is located, the subscribers' lines are provided with individual line switches of the rotary type. These switches have access to relatively large groups of twenty-five trunk lines each, and consequently secondary line switches are not necessary. The inter-office trunk lines extending from the originating exchange to the second exchange, which are the only inter-office trunk lines shown, are all in a single group, this result being accomplished by the use of secondary line switches of the rotary type between the first selectors in the originating office and the outgoing trunk repeaters.

Proceeding now with the operation, the process of establishing the connection referred to extending from the calling station A, Fig. 1, to the called station A', Fig. 4, will now be explained, it being assumed that the telephone number at the called station is #2345. When the receiver is removed at the calling station a circuit is completed over the line conductors 11 and 12 for the line relay 16 of the primary line switch P. Upon attracting its armatures 23 and 24 relay 16 closes parallel energizing circuits through the pull down winding 17 and the holding winding 18 of the line switch, both of these circuits including the lower low resistance winding of the line relay and the grounded conductor 25. This latter conductor, it may be mentioned, extends to ground through the left-hand winding of supervisory relay 39 of the master switch M, and may be considered for all practical purposes to be directly connected to ground inasmuch as the left-hand winding of relay 39 has a resistance of less than 1 ohm. The lower winding of the line relay 16 is also very low in resistance as stated (about 10 ohms preferably) and a heavy current flow is at once established in the pull in winding 17, with the result that the cutoff armature 28 and the plunger arm 29 are both immediately operated, the former separating contact springs 20 and 22 from contact springs 19 and 21, respectively, and the latter forcing the bank springs 30, 31, 32, and 33 into engagement with bank contacts 34, 35, 36, and 37, respectively. Although the initial energizing circuit for the line relay 16 is opened by the separation of the cut off springs controlled by armature 28 the line relay is not deenergized, but remains locked up by the circuits through its lower winding. By the engagement of bank springs 30 and 33 with the bank contacts 34 and 37 the line conductors of the calling line are extended through to the conductors 50 and 53 of the trunk extending to the secondary line switch S. By the engagement of bank spring 32 with bank contact 36 the holding or cut-off winding 18 of the line switch is connected

with the release trunk conductor 52 of the trunk line extending to the secondary line switch S. This holding winding now has its upper terminal connected to ground by way of armature 24 and the lower winding of the line relay 16, and a ground potential is thus placed upon conductor 52. A circuit is thus completed over the branch conductor 27 extending to the master switch bank contact upon which the master switch wiper is now resting for energizing the starting relay 40 of the master switch M. Upon energizing, relay 40 closes a circuit for the locking magnet 41, which unlocks the master switch shaft and thus brings about the re-alignment of all the idle line switch plungers in front of the next idle trunk line. The locking relay 41 also closes a circuit for the open main relay 42 which, upon energizing, disconnects the common conductor 26 from the negative pole of the battery in order to prevent any of the line switches from being operated until the master switch comes to rest. It will be observed that there is a resistance 38 which is shunted around the contacts of relay 42. This resistance is about 300 ohms and is high enough to prevent the operation of the line switches, while still furnishing enough current to maintain the line relay 16 locked up. The provision of this resistance is not absolutely necessary in all cases, since the line relay may remain locked up over the circuit through the holding winding 18, which is not interrupted by the operation of the master switch; but this holding winding is of very high resistance, about 1300 ohms, and the resistance 38 is added as a precautionary measure in order to insure the holding up of the line relay and in order to eliminate the necessity of careful adjustments.

It will be observed that as soon as the line relay energizes and the circuit is completed for the holding winding 18, ground potential will be placed on the private normal conductor 14, which extends to multiply connected test contacts in the banks of the connector switches which have access to the line of station A. This renders the calling line busy and inaccessible to other calling lines.

The operation of the secondary line switch S follows instantly after the operation of the primary line switch P and is brought about by the engagement of bank spring 31 with the bank contact 35. This closes a circuit over conductor 51 for the pull in winding 54 of the secondary line switch which, upon energizing, attracts both the cut-off armature 56 and the plunger arm 57, the former being effective to shift the contact springs 58, 59, and 60 and thereby connect the high resistance holding winding 55 in series with the pull down winding 54, and the latter being effective to force the bank springs 70,

71, 72, and 73 into engagement with the bank contacts 74, 75, 76, and 77, respectively. By the engagement of bank springs 70, 72, and 73 with bank contacts 74, 76, and 77, respectively, the conductors 50, 52 and 53 of the trunk line incoming to the secondary line switch are extended into connection with the conductors 80, 81, and 82 of the trunk line extending to the first selector D. By the engagement of bank spring 71 with the bank contact 75 a circuit is completed over conductor 63 and through the master switch wiper to the starting relay 64 of the secondary master switch M'. The starting relay 64, upon energizing, closes a circuit for the locking relay or magnet 65, which unlocks the master switch shaft and advances the plungers of all the idle line switches into position opposite the next idle trunk line. The open main relay 66 is energized in parallel with the locking magnet 65 and disconnects the common conductor 62 from the negative pole of battery in order to prevent the operation of any of the secondary line switches while the master switch is in operation.

When the calling line is extended to the first selector D, as described in the foregoing, the line relay 100 is energized over the line circuit and at its armature 112 closes a circuit through the upper winding of the slow acting release relay 101. Upon energizing, the latter relay prepares a circuit for the vertical magnet 105 at its armature 113, prepares certain other circuits, which will be described, at its armature 114, and at armature 115 connects ground to the release trunk conductor 81. By the latter operation a holding circuit is completed for the holding winding 18 of the primary line switch P which may be traced from grounded armature 127 of the switching relay 104 by way of the working contact of armature 115 and the said armature, conductor 81, bank contact 76, bank spring 72, conductor 52, bank contact 36, bank spring 32 and the holding winding 18 to battery. This circuit serves to maintain the holding winding 18 energized throughout the connection. It will be observed now that since direct ground is supplied to the holding winding 18 over this new path, the lower winding of the line relay 16 will be short circuited, and the said relay will deenergize. As soon as armatures 23 and 24 are reattracted the locking circuit through the lower winding of the line relay is permanently opened.

The calling subscriber may now proceed to operate his calling device in accordance with the first digit in the desired number. As a result two interruptions are produced in the circuit of the line relay 100 of the selector D and this relay is deenergized twice momentarily, each time sending an impulse of current to the vertical magnet 105 over

the following circuit: From the grounded armature 128 by way of the resting contact of said armature, normally closed contact springs 110 and 111, armature 113 and its working contact, armature 117 and its resting contact, and the winding of the vertical magnet 105 to battery. By the operation of the vertical magnet the switch shaft is raised two steps and the wipers 140, 141, and 142 are brought to rest opposite the second level of bank contacts. Although the energizing circuit of the relay 101 is interrupted each time the line relay transmits an impulse to the vertical magnet, said relay does not fall back at this time on account of its slow releasing characteristic produced by the now short circuited lower winding. This winding is of low resistance, preferably about 25 ohms. At the first vertical step of the shaft 20 the off normal springs are shifted in the usual manner and by the closure of off normal springs 123 a circuit is completed for the stepping relay 103 which extends from the grounded armature 128 by way of the resting contact of said armature, the working contact of armature 114 and the said armature, armature 118 and its resting contact, off normal springs 123 and the winding of relay 103 to battery. Upon energizing, relay 25 103 establishes a locking circuit for itself at its armature 120 over a path which will be sufficiently obvious, and at its armature 119 prepares a circuit for the rotary magnet 106. The off normal springs 122 are closed at the same time as springs 123 and by their engagement the high resistance relay 102 is connected in multiple with the upper winding of relay 101. It follows, therefore, that each time the line relay energizes following a momentary deenergization a current impulse will be transmitted through the winding of relay 102, but this relay is of extremely high impedance and resistance (about 5000 ohms preferably) and does not 30 operate during the vertical operation of the switch. At the end of the series of interruptions for the first digit in the number, the line relay 100 comes to rest in energized position and the circuit of relay 102 is permanently closed. Relay 102 is accordingly energized and at its armature 117 opens the circuit of the vertical magnet 105, while at armature 118 a circuit is closed for the rotary magnet 106 which extends from the 35 grounded armature 128 by way of the resting contact of said armature, working contact of armature 114 and the said armature, armature 118 and its working contact, working contact of armature 119 and the said armature, and the winding of the rotary magnet 106 to battery. The rotary magnet is energized when its circuit is closed and by rotating the switch shaft one step brings the switch wipers into engagement with the first 40 set of bank contacts in the level opposite

which they were raised. At the same time the rotary magnet opens its interrupter contact and thus breaks the locking circuit of the stepping relay 103, which accordingly de-energizes and breaks the circuit of the rotary magnet, which then deenergizes also and again closes its interrupter contact. 70

The operation now depends upon whether the first trunk line is busy or idle. If this trunk line is busy there will be a ground potential on the test contact with which the test wiper 141 is in engagement and a circuit will be completed by way of the said test wiper for again energizing the stepping relay 103. This relay is thus operated again 75 and the rotary magnet operates likewise to advance the switch wipers into engagement with the next set of bank contacts, at the same time causing the stepping relay to de-energize. This operation in which the stepping relay and the rotary magnet are energized alternately will continue as long as the test wiper 141 continues to engage grounded or busy test contacts, but as soon as an idle trunk line is reached, which we 80 will assume to be the trunk line extending to the secondary rotary line switch S^2 , the test wiper 141 will find no ground potential on the associated test contact, which is the test contact 144, and the stepping relay 103 85 will not again be energized. Instead, the switching relay 104, which has heretofore been short circuited, will be operated by current flow over a circuit which may be traced from the grounded conductor 81 by way of the winding of the switching relay 104, interrupter contact of the rotary magnet 106, off normal springs 123 and the winding of the stepping relay 103 to battery. Upon energizing, relay 104 disconnects ground from 90 various circuit conductors in the selector at armature 128, connects the incoming release trunk conductor 81 to the test wiper 141 at armature 126, and at armatures 125 and 129 disconnects the conductors 80 and 82 95 of the trunk line from the windings of the line relay 100 and extends them by way of wipers 140 and 142, bank contacts 143 and 145, and trunk line conductors 146 and 148 to the winding of the line relay 161 of the 100 secondary line switch S^2 and to ground, respectively. In addition to the foregoing, at its armature 127 the switching relay 104 removes the short circuit normally existing around the lower winding of the release 105 relay 101. The slow acting characteristic of the relay is thus destroyed, and the relay remains locked to the holding circuit which includes the release trunk conductor 81, current being supplied to conductor 81 110 through the lower winding of relay 101 for maintaining relay 104 of the selector and the holding winding 18 of the primary line switch energized. As mentioned hereinbefore, the lower winding of relay 101 is of 115

comparatively low resistance, and the test contact 144 and its multiples in the banks of the other selector switches are brought sufficiently near to ground potential to render the trunk line extending to the secondary line switch S^2 busy.

When the calling line is extended to the secondary line switch S^2 the line relay 161 is energized and closes a circuit at its armature 167 which extends from the now grounded release trunk conductor 147 by way of armature 167 and its working contact, winding of the switching relay 160 and the winding of the stepping magnet 162 to battery. At the same time relay 161 connects the test wiper 181 to the above circuit at a point midway between the said switching relay and the stepping magnet, this connection being established at armature 168. The operation now depends upon whether the trunk line with which the wipers of the secondary line switch are in engagement is busy or idle. If such trunk line is busy the test contact engaged by the test wiper 181 will be grounded, the switching relay 160 will be short circuited, and the stepping magnet 162 which interrupts its own circuit will act as a buzzer to advance the switch wipers step by step in search of an idle trunk line. This movement of the switch will continue until the test wiper 181 arrives at an ungrounded test contact. Assuming that the trunk line which extends to the repeater R, Fig. 3, is the first idle trunk line encountered, when the test wiper arrives at test contact 184 it will find no ground potential and the operation of the rotary magnet will cease. Relay 160 being now no longer short circuited will energize at once in series with the rotary magnet, the latter remaining inoperative due to the high resistance of the switching relay. Upon energizing, switching relay 160 connects the release trunk conductor 147 to the test wiper 181 at armature 165, thus making the selected trunk line busy, establishes a holding circuit for itself at its armature 164, and at armatures 163 and 166 disconnects the trunk conductors 146 and 148 from the winding of the line relay 161 and from ground, respectively, and extends them by way of wipers 180 and 182, bank contacts 183 and 185, trunk conductors 186 and 188, normally closed contact springs of the reversing relay 205, and the left-hand windings of the repeating coil at the repeater R to the upper and lower windings of the double wound line relay 200.

The calling line having been extended to the line relay 200 of the repeater, this relay is energized in the usual manner and closes a circuit for the slow acting release relay 201. Upon energizing in turn relay 201 completes a holding circuit at its armature 213 which may be traced as follows: From the grounded armature 213 by way

of the working contact of said armature, release trunk conductor 187, bank contact 184, test wiper 181, working contact of armature 165 and the said armature, release trunk conductor 147, bank contact 144, test wiper 141 and armature 126 and its working contact to release trunk conductor 81 where it joins the previously described holding circuit extending back to the holding winding of the primary line switch P. This holding circuit now supplies current to switching relay 160 of the secondary line switch S^2 , the switching relay 104 of the first selector D, and the holding winding 18 of the primary line switch in order to maintain these relays energized. Since the holding circuit is directly grounded at the repeater R, it will be evident that the lower winding of the slow acting release relay 101 will now be short circuited. It follows, therefore, that relay 101 is deenergized and disconnects itself from the release trunk conductor 81 at armature 115.

Continuing now with the operations at the repeater R, when the release trunk conductor 187 is grounded a circuit is closed through the right-hand winding of the shunt field relay 204. Owing to the fact that there is a closed magnetic circuit through the left-hand core of this relay the flux is diverted away from the armature and the relay is not operated at this time. In addition to grounding the release trunk conductor 187, the slow acting relay 201 prepares a circuit for relay 203 at armature 208, and at armature 209 closes a circuit for the slow acting relay 202. Upon energizing, the latter relay establishes a locking circuit for itself at armature 211. Still another result of the energization of relay 201 is the closure of a bridge across the conductors 230 and 232 of the trunk line extending to the second exchange and there terminating in the incoming selector E. This bridge may be traced from conductor 230 by way of the upper right-hand winding of the repeating coil, the left-hand winding of shunt field relay 204, the lower right-hand winding of the repeating coil, armature 207 and its working contact (line relay 200 being now in energized position), and the working contact of armature 210 and the said armature to conductor 232. Upon the closure of this bridge the line relay 250 of the selector E in the distant exchange is energized and completes a circuit for the slow acting release relay 251. Upon energizing, relay 251 prepares a circuit for the vertical magnet 256 at armature 261 and at armature 262 connects ground to conductor 231.

The calling subscriber may now operate his calling device in accordance with the next digit in the desired number, thereby producing three interruptions in the circuit

of the line relay 200 of the repeater R. In response to these interruptions of its circuit, relay 200 deenergizes momentarily three times and at each deenergization transmits a current impulse through the lower winding of relay 203. The operation of relay 203 at this time, however, is of no particular effect. In addition, the line relay 200 opens the bridge across the trunk conductors 230 and 232 three times at armature 207, whereby three interruptions are produced in the circuit of the line relay 250 of the selector E. In response to these interruptions of its circuit the line relay 250 deenergizes three times and at each deenergization closes a circuit for the vertical magnet 256 in series with the slow acting series relay 252. By the operation of the vertical magnet the selector shaft is raised three steps and the wipers 280, 281, and 282 are brought to rest opposite the third level of bank contacts. Relay 252 is energized in series with the vertical magnet and being slow acting retains its armature attracted during the vertical operation of the switch. At the first vertical step the off normal springs 259 are closed and since relay 252 is now in operated position a circuit is closed through the stepping relay 254. Upon energizing, relay 254 establishes a locking circuit for itself at its upper armature and at its lower armature prepares a circuit for the rotary magnet 257.

At the end of the vertical movement of the switch the slow acting relay 252 is deenergized and closes a circuit for the rotary magnet 257, which is accordingly operated to rotate the switch shaft one step and bring the switch wipers into engagement with the first set of bank contacts in the level opposite which they are raised. At the same time the rotary magnet breaks the locking circuit of the stepping relay 254, and this relay is deenergized to open the circuit of the rotary magnet, which then deenergizes also and again closes its interrupter contact. The usual trunk selecting operation is thus initiated, and in case the test contact associated with the first trunk line is grounded the trunk selecting operation will continue automatically, the stepping relay 254 and the rotary magnet 257 being energized alternately to advance the switch wipers step by step as long as the test wiper 281 continues to engage grounded test contacts. When the wipers arrive at an idle trunk line, which we will assume to be the trunk line extending to the connector H, Fig. 4, the test wiper 281 will find no ground potential on the test contact 284, the stepping relay 254 cannot again be energized, and rotation of the switch will cease. The switching relay 255, which has heretofore been short circuited, is now energized over a circuit extending from the grounded conductor 231, through the

winding of said switching relay 255 and by way of the interrupter contact of the rotary magnet, the off normal springs 259, and the winding of the stepping relay 254 to battery. Upon energizing, relay 255 connects the grounded conductor 231 to the test wiper 281 at armature 265 in order to make the selected trunk line busy at once, and at armature 266 closes a circuit through the upper winding of relay 253. Relay 253 is accordingly energized and at armature 269 connects its lower winding with conductor 231, the said winding being, however, short circuited for the present by the ground at armature 262 of relay 251. In addition to the foregoing, at armatures 264 and 267 switching relay 255 disconnects the incoming trunk conductors 230 and 232 from the winding of the line relay 250 and extends them by way of wipers 280 and 282, bank contacts 283 and 285, conductors 286 and 288 and normally closed contact springs of the reversing relay 307 to the upper and lower windings of the line relay 300 of the connector H. At the selector E when the line relay 250 is disconnected, as explained, it falls back at once and breaks the circuit of the slow acting release relay 251 which deenergizes also an instant later. At its upper armature relay 251 breaks the circuit through the upper winding of relay 253, and at armature 262 it removes the short circuit from the lower winding of said relay. By reason of the latter operation, in case the release trunk conductor 287 has not yet been grounded at the connector H, ground potential will be supplied to the conductor 231 through the lower winding of relay 253, and relays 253 and 255 will be held locked in a local circuit. As soon as the line and release relays 300 and 301 of the connector H pull up, due to the extension of the calling line to the trunk conductors 286 and 288, the latter relay connects ground to the conductor 287 at armature 312 and the lower winding of relay 253 is short circuited. It will be evident then that relay 253 will be deenergized, similar to the way in which relay 101 of the selector D deenergized, and will disconnect itself from conductor 231 by retracting armature 269.

The connection has now been extended as far as the connector H, Fig. 4, and the calling subscriber may proceed to call the remaining two digits in the desired number. When the third digit 4 is called a series of four interruptions is produced in the circuit of the line relay 200 of the repeater R and this relay is operated in the manner previously explained to repeat the interruptions into the circuit of the line relay 300 of the connector H. Relay 300 is accordingly deenergized four times and at each deenergization transmits an impulse of current to the vertical magnet 308 over the following

circuit: From the grounded armature 311 by way of the resting contact of said armature, armature 313 and its working contact, off normal springs 328 and 340, winding of 5 the slow acting series relay 302, and the winding of the vertical magnet 308 to battery. By the operation of the vertical magnet the switch shaft is raised step by step until the wipers 350, 351, 352, and 353 stand 10 opposite the fourth level of bank contacts. Relay 302 is energized in series with the vertical magnet and being slow acting retains its armature in operated position while impulses are being transmitted to the vertical magnet. By the attraction of armature 15 314 against its front contact, relay 302 maintains the vertical magnet circuit closed notwithstanding the shifting of the off normal springs, which occurs at the first vertical 20 step of the switch. At the end of the vertical movement of the switch the relay 302 is deenergized and transfers the operating circuit to the rotary magnet 309.

When the calling subscriber operates his 25 calling device for the next digit, which is the digit 5, five interruptions are produced in the circuit of the line relay 200 of the repeater R which are repeated as before into the circuit of the line relay 300 of the connector H. This time, however, the line relay 300 transmits a series of impulses to the rotary magnet 309 over a circuit which may be traced as follows: From grounded armature 311 by way of the resting contact of 30 said armature, armature 313 and its working contact, off normal springs 328 and 329, armature 314 and its resting contact, armature 319 and its resting contact, armature 325 and its resting contact, and the winding 35 of the rotary magnet 309 to battery. By the operation of the rotary magnet the switch shaft is rotated five steps and the switch wipers are brought to rest in engagement with the particular set of bank contacts in 40 which the line of substation A' is terminated, these bank contacts being indicated by the reference numerals 354, 355, 356, and 357. The slow acting relay 305 is energized in parallel with the rotary magnet 309 while 45 the switch is rotating, and at armature 321 connects the test wiper 352 with test relay 304. At the same time relay 305 closes a shunt circuit around break contact at armature 319 of the test relay at its armature 322, and thus avoids any possibility of the rotary 50 magnet circuit being opened by the operation of the test relay in case the test wiper 352 should engage a grounded contact while the switch is rotating. At the end of the rotary 55 movement of the switch slow acting relay 305 will deenergize, and the further operation at the connector will depend upon whether the line of substation A' is busy or not.

Assuming first that the line is busy, when

the test wiper 352 engages the test contact 356 it finds a ground potential on said test contact and the test relay 304 will be energized. Upon energizing, relay 304 prepares a locking circuit for itself at armature 318, 70 which is completed as soon as the slow acting relay 305 deenergizes an instant later. At its armature 319, relay 304 transfers the operating circuit from the rotary magnet 309 by way of the fourth wiper 351 and associated bank contact 355 to the meter C, associated with the line of substation A', and at armature 320 connects a lead from the busy signalling machine to the lower side of the trunk line. By the latter operation, the calling subscriber is given an audible busy signal in the usual manner to advise him that the desired line is engaged. Upon hanging up his receiver the calling subscriber will release all of the automatic 85 switches, but the full explanation of these releasing operations will be deferred until later. It will be convenient to explain at this time, however, that when the line relay 300 of the connector H is deenergized 90 responsive to the replacement of the receiver at the calling station, an impulse of current is transmitted to the operating magnet of the meter C, and the meter is operated to register the attempted connection. This circuit is, of course, broken immediately by the deenergization of the slow acting release relay 301, which falls back an instant after the line relay 300 and closes the circuit of release magnet 310 in order to release the connector switch. Meters, such as the meter C, are provided for certain subscribers' lines when called for in order to register the number of times such subscribers are called when 95 busy.

It will be assumed now that the line of substation A' was idle when called, as described in the foregoing, and the establishment of the connection will be proceeded with. Under the assumption that the line 100 is in idle condition the test contact 356 will not be grounded and when the line is connected with by the connector H, the test relay 304 will not be energized. Then, when the slow acting relay 305 falls back an instant later a circuit is completed for the switching relay 306 which extends as follows: From ground at armature 312 by way of conductor 346, armature 318 and its resting contact, upper winding of the switching 105 relay 306, resting contact of armature 321 and the said armature, test wiper 352, test contact 356, private normal conductor 371, winding of the switching relay 360 of the line switch P' and the winding of the stepping magnet 361 to battery. Upon the closure of this circuit relays 306 and 360 are energized in series and the latter relay 110 disconnects the line conductors 370 and 372 of the line extending to substation A' from 115 120 125 130

the winding of the line relay 362 and from ground, respectively. By reason of a mechanical interlocking device controlled by the armature of line relay 362, the armature of the switching relay 360 is operated only about half way, and the wipers of the line switch are not connected up.

At the connector H, when the switching relay 306 is energized it establishes a locking circuit for itself at armature 326, opens the rotary magnet circuit at armature 325, connects direct ground to the test wiper 352 at armature 324, disconnects the condenser 347 from in bridge of the line relay 300 at armature 348 and at armatures 323 and 327 connects up the line wipers 350 and 353. By the latter operation a signalling circuit is completed over which ringing current from the generator GEN is projected to operate the bridged ringer at substation A', thereby notifying the subscriber that he is wanted at the telephone. The upper winding of the ring cut-off relay 303 is included in the signalling circuit, and when the called party responds by removing his receiver the said ring cut-off relay is operated, establishing a locking circuit for itself at its armature 316. In addition, the ring cut-off relay 303 breaks the ringing circuit at armatures 315 and 317 and at the working contacts of these same armatures finally completes the talking circuit. The transmitter at substation A' is now supplied with talking current through the windings of the double wound back bridge relay 307 which is accordingly energized and reverses the incoming trunk conductors 286 and 288 as regards their connection to the windings of the line relay 300. This operation reverses the direction of current flow over trunk conductors 230 and 232, and also, therefore, the direction of current flow through the left-hand winding of the shunt field relay 204 at the repeater R. This winding, which is included in the circuit of the line relay, is normally energized so that the polarity of the associated left-hand magnet core is opposed in sign to the polarity of the right-hand core; that is, if the upper end of the right-hand core is positive, the upper end of the left-hand core will be negative. Thus, under normal conditions before the called party answers the magnetic flux generated will flow through the two magnet cores in series and will not effect the armature of the relay. When the current in the left-hand winding is reversed, however, the polarity of the left-hand core is reversed also, and the magnetic flux produced will necessarily flow through the two cores of the magnet in parallel and through the armature of the magnet and the heel piece (not shown). Accordingly the armature is attracted and a circuit is completed for the reversing relay 205, which is at once energized in order to reverse the direction of current flow in the

trunk conductors 186 and 188 and in the calling subscriber's line. These reversing operations although of no particular utility in connection with the apparatus shown herein, are required on occasion for the purpose of 70 operating a meter, or other device, and since they are ordinarily provided for in working exchanges the circuits are so illustrated herein.

The desired connection has now been established and the subscribers may converse as desired. When the conversation is finished, both parties will hang up their receivers, and the replacement of the receiver at the calling station A brings about the release of the connection, as before stated. These releasing operations will now be considered. When the receiver is replaced the circuit of the line relay 200 of the repeater R is broken and this relay accordingly deenergizes and breaks the circuit of the slow acting release relay 201 and also opens the bridge across the trunk conductors 230 and 232 at armature 207. By the latter operation the circuit of the line relay 300 of the connector H is broken and relays 300 and 301 deenergize to cause the release of the connector H, as has already been briefly explained. It will be understood, of course, that during the release of a successful connection the meter C is not operated, due to the fact that the test relay 304 is not energized. The release relay 301 also disconnects ground from release trunk conductor 287, thereby breaking the holding circuit of the switching relay 255 of the selector E. Upon the deenergization of the switching relay 255 the selector E is restored to normal through the medium of the release magnet 258.

Returning to the repeater R, when the line relay 200 falls back it also closes a circuit through the lower winding of relay 203, which is accordingly energized to disconnect ground from the release trunk conductor 187 at armature 217 and to open the locking circuit of relay 202 at armature 212. An instant later relay 201 deenergizes and breaks the initial energizing circuit of relay 202 at armature 209, breaks the energizing circuit of relay 203 at armature 208, and immediately closes an alternative energizing circuit for relay 203 at the resting contact of armature 210. Relay 202 being slow acting remains in operated position for an instant after its circuit is broken at armature 209 and maintains the previously mentioned energizing circuit for the upper winding of relay 203 closed at armature 215. This energizing circuit includes outgoing trunk conductors 230 and 232, and the line relay of the selector E or the line relay of the connector H, depending upon how far the releasing operations have proceeded. The upper winding of relay 203 is of very high resistance and while it does not interfere with the re- 120 125 130

lease of the connector H it retains relay 203 in operated position until the slow acting relay 202 falls back and disconnects it from in bridge of the trunk conductors 230 and 232. The release of the secondary line switch S², the selector D, and the primary and secondary line switches P and S, occurs when ground is removed from the release trunk conductor 187 by the deenergization 10 of slow acting release relay 201. When ground is removed from release trunk conductor 187, relays 160 and 104 of the secondary line switch S² and the selector D, respectively, and the holding winding 18 of the primary line switch P are deenergized and these switches are restored in the well known manner, the selector D being returned to normal by the operation of the release magnet 107. When the primary line 20 switch P withdraws its plunger from the bank, ground is disconnected from conductor 51, whereupon the secondary line switch S is released also.

Having described the ordinary operation 25 of the system, it will be convenient now to describe certain of the features of the invention more in detail, and to call attention to certain other features which could not readily be explained while describing the establishment of an ordinary connection. The first thing which will be considered is the locking circuit which is applied to certain 30 of the switches for bridging over the time interval in which the connection is extended to the next succeeding switch, and which incidentally provides for locking up the connection whenever an open trunk line is encountered. Considering the primary line switch P, Fig. 1, it has been customary to make the line relay of a line switch of this character slow acting by means of a copper slug in order to enable it to hold the pull down winding energized until ground is fed back over the release trunk conductor from the first selector. These slow acting line relays are difficult to adjust, since they are only energized for an instant and consequently do not become fully saturated, which makes it hard to obtain the desired slow releasing 45 characteristic. The locking arrangement for the line relay of a switch of this type, such as is shown for the line relay 16 of the line switch P, entirely eliminates all of the trouble heretofore encountered due to the use of the slow acting line relays.

This circuit arrangement also introduces a decided advantage in the case of the plunger type secondary line switches, such as the line switch S, Fig. 1. It has been necessary heretofore to provide a line switch of this type with a low resistance slow acting relay included in the open main conductor 62, or rather in the branch thereof which is individual to the line switch, which relay when energized connects ground to the release

trunk conductor 52, thus providing a temporary holding circuit for retaining the primary line switch in operated position until the relays in the first selector have had time to energize. It will be clear that the present 70 circuit arrangement renders the relay referred to entirely unnecessary, and the secondary line switch as shown in the drawing requires only a single core having the pull down and holding windings as illustrated. 75

Considering now the feature of locking the connection in case an open trunk line is encountered, it will be clear that when a call is made from the substation A, as described in the foregoing pages, if one of the conductors of the trunk line extending to the secondary line switch S is open, or if one of the conductors of the trunk line extending to the first selector D is open, or if either of these switches or the primary line switch fails to function properly, the release trunk conductor 52 will not be grounded at the first selector switch, the lower winding of the line relay 16 will not be short circuited, and this relay will, therefore, remain locked 90 up. The locking circuit includes the common conductor 25 and the left-hand winding of supervisory relay 39 which is operated also to light the supervisory lamp L. This lamp is provided to attract the attention of a switch-board attendant who will immediately proceed to investigate the trouble and correct it. If desired an audible alarm of some kind can be operated at the same time as the lamp L in any convenient or suitable manner. It will be appreciated 95 that the arrangement described provides an effective method of locating trouble speedily and surely, while at the same time the annoyance to the subscribers concerned is reduced to a minimum, for the attendant when notified of a case of trouble is able at the same time to ascertain the number of the subscriber who has met with difficulty and can reassure or assist him in getting his 100 number before he has had time to make a complaint.

The locking circuit for the line relay of a line switch is also applicable to line switches of the rotary type, as will be seen by referring to the circuit of line switch P', Fig. 4. Considering the line relay 362 of this switch, the armature 366, which ordinarily is connected to ground, according to the present invention is connected by way of a 110 common conductor through the low resistance supervisory relay 365 to ground, and a low resistance locking winding is substituted for the usual copper slug. The operation so far as the invention is concerned is 115 identical with the operation described in the case of the plunger type line switch P, Fig. 1. When the switching relay 360 is energized upon an idle trunk line being selected, this relay and the line relay remain 120 125 130

locked up in series with the supervisory relay 365 until ground is fed back from the first selector over the release trunk conductor, such as the conductor 381 of the selected trunk line, which operation will short circuit the lower winding of the line relay and permit it to be energized. It will be clear that if there is anything wrong with the trunk line or the first selector switch which would prevent ground being supplied to the release trunk conductor, the line relay will remain locked up, relay 365 will remain energized, and the lamp L⁴ will remain lighted to signal the attendant.

Attention may now be directed to the manner in which the locking feature is applied to the first selector D. It will be recalled that when the selector D establishes connection with an idle trunk line and the switching relay 104 operates, ground is supplied to the release trunk conductor 81 through the lower low resistance winding of the release relay 101, said relay remaining locked up until ground is connected to the release trunk conductor 187 at the repeater R. If either of the trunk lines beyond the selector D is defective to an extent which makes it inoperative the release trunk conductor 147 will not be grounded and since the lower winding of relay 101 will not be short circuited the connection will remain locked up. Switching relay 104 when it energizes closes a circuit for the lamp L' at armature 127. If the apparatus functions properly relay 101 will de-energize an instant later and will open this circuit at armature 116, but if relay 101 fails to deenergize, as is the case when a defective trunk line is encountered, lamp L' will remain lighted to signal the attendant. The pilot relay 130 may be common to a plurality of lamps, such as the lamp L', and can be used to sound an audible alarm if desired.

As in the case of the local secondary line switch S, a decided advantage is also introduced in the case of the outgoing secondary line switch S². Heretofore an outgoing secondary line switch of this type has been provided with a slow acting line relay, instead of an ordinary quick relay like the line relay 161. This slow acting relay was provided with spring contacts for grounding a release trunk conductor, such as conductor 147, in order to maintain the preceding selector switch in operated position until ground could be fed back from the repeater in the trunk line to which the connection was extended. It will be clear that when a selector such as the selector D is used, which feeds ground forward over the release trunk, this arrangement in the outgoing secondary line switch is entirely unnecessary. As shown in the drawing of the line switch S², Fig. 2, no slow acting relays whatever are

required and a circuit arrangement is thus provided having the maximum simplicity and effectiveness in operation.

In the case of the incoming selector E, Fig. 3, the locking arrangement has been applied to a standard selector circuit by the use of an additional relay, which is the relay 253. By using a separate relay for the locking circuit an ordinary slow acting release relay, such as the release relay 251 can be used for controlling the ordinary operation of the selector and it has been found desirable to do this in some cases. The operation of relay 253 will be sufficiently understood from what has been said to make it unnecessary to go into further details, but it may be mentioned that in case the selector E becomes locked on an open trunk, the relay 253 will hold the circuit of the lamp L³ closed in order to signal the switch-board attendant.

Referring now to the repeater R shown in Fig. 3, the circuit of this switching mechanism is also arranged in a special manner to take care of trouble due to open trunk lines. In this case, however, as the circuits are ordinarily intended to operate, if the outgoing trunk line from the repeater is open, the connection from the calling subscriber will not be locked up as in the preceding cases, but will be disconnected when the calling subscriber hangs up. The trunk line, however, extending to the repeater R will be made busy, so as to prevent other calling subscribers from obtaining access to it. The manner in which this is done may be described briefly by considering the operation which takes place when the calling subscriber hangs up his receiver after an unsuccessful connection, caused by a defect in the trunk line comprising conductors 230 and 232. When the receiver is replaced the line relay 200 falls back and breaks the circuit of the release relay 201, at the same time closing a circuit for relay 203, which energizes to open the locking circuit of relay 202. After an instant the release relay 201 falls back, removes ground from the release trunk conductor 187 in order to release the preceding switches, breaks the circuit of relay 202, also the circuit of relay 203, and finally closes the upper winding of the latter relay in bridge of the trunk conductors 230 and 232. In the event the trunk line is in operative condition, relay 203 will be held energized by means of its upper winding and the slow acting relay 202 will become unlocked, but in the present case since the trunk line is assumed to be open relay 203 will fall back immediately, and will close the locking circuit of relay 202 before the said relay has time to fall back. The release trunk conductor 187 is now connected to ground by way of armatures 214 and 217, rendering the trunk line busy. In addition, since the

release relay 201 is now deenergized a circuit is closed through the supervisory lamp L² and the pilot relay 225, whereby the attention of the switch-board attendant is attracted to the location of the trouble.

With the circuits in the condition shown in the drawing, if a calling subscriber extends a connection to the repeater R at a time when the trunk line beyond is open the connection will not be locked up as in the case of a line switch or selector switch encountering an open trunk line, but the subscriber will be able to release the switches and call again, as explained in the preceding paragraph. Under certain circumstances, however, it is desirable to lock unsuccessful calls at repeaters, as well as at the line switches or selector switches, and if so the keys, such as the key K, associated with the repeaters, are operated by the attendant. Key K is of the self locking type and when in operated position short circuits the break contact at armature 217 of relay 203. It will be clear that with the circuit of the repeater in this condition ground will be maintained on the release trunk conductor 187 as long as the slow acting relay 202 remains energized and since this relay remains locked up if a trunk line on the outgoing side of the repeater is open the calling subscriber will be unable to disconnect. With key K in operated position, a further advantage is procured in that the attendant at the second exchange can prevent a calling subscriber from releasing by short circuiting the line conductors of the trunk incoming to the selector E. It is necessary to do this sometimes in tracing back annoyance calls. For instance if a subscriber in the second exchange is being annoyed by someone in the first exchange, a signalling device may be associated with the complaining subscriber's line to notify the switch-board attendant when a call is received at such line. When the signal is operated the attendant will listen in on the line, and if he finds that it is an annoyance call, he will immediately short circuit the line conductors of the trunk line in use. This prevents the subscriber who is causing the trouble from releasing, and will enable the switch-board attendant in the originating office to trace back the connection and ascertain the number of this subscriber.

Another feature of the invention to which attention is now directed relates to the use of a condenser in a switch controlling circuit. Referring to the selector D, in Fig. 2, it will be observed that there is a condenser connected directly across the incoming trunk line conductors at the terminals of the line relay 100. This condenser absorbs the high voltage kick caused by breaking the circuit of the line relay during the transmission of operating impulses and enables the relay to

respond accurately to impulses throughout a wide variation of line conditions. Although condensers have been used at the substations before this, it has been demonstrated by tests that better results are secured if the condenser is located at the exchange as close to the switch as possible, and it is preferable then to connect it directly across the line relay terminal as shown. Line relay 250 of the selector E, Fig. 3, is provided with a similar condenser. It will be observed that these condensers are across the talking circuit only while the associated switches are being operated, and as each switch extends the connection to the next switch in the series, the condenser is disconnected along with the associated line relay. The line relay 300 of the connector H is also shunted by a condenser. Since the line relay of the connector remains across the line during conversation, it is necessary to provide a special arrangement for disconnecting the condenser in order not to shunt the talking currents. This arrangement is simple and consists of a pair of contact springs on the switching relay 306, as shown in the drawings.

Another feature of the invention which will be described a little more fully consists in the provision of make-before-break contact springs on the line relay 100 of the selector D. Contact springs of the make-before-break variety have a decided advantage over the ordinary contact springs, such as are shown on the line relay 250 of the selector E, Fig. 3, in that the time interval during which current is supplied to the slow acting release relay during the transmission of impulses is considerably longer, and there is on this account less danger of the release relay falling back during a series of impulses. With the selector circuit using the ordinary slow to deenergize change-over relay, such as is shown in the case of the selector E, however, make-before-break contact springs cannot be used on account of the danger of over-heating the vertical magnet. For instance, a subscriber's line might have a high resistance short circuit across it, due to some kind of line trouble, which would operate the primary line switch and extend the connection to a first selector. Assuming that this first selector is a standard switch, except that it has make-before-break contacts, the resistance of the short circuit might be low enough to energize the line relay just sufficient to close all three contact springs together without separating the brake contact, in which case the release relay would energize and close the vertical magnet circuit, which circuit would then remain permanently closed. It will be seen that the danger of injuring the selector vertical magnets renders it impractical to use the make-before-break contact spring arrangement on the line relays of the ordinary type selectors,

but in the case of the selector D the circuit arrangement is such that this make-before-break contact spring arrangement can be used to good advantage and without introducing any trouble.

The operations which take place at the selector D in case a leaky line, or a line having a high resistance short circuit across it, is extended to the selector will now be explained. Certain details of the winding and mounting of the relays 100, 101, and 102 should first be explained, however, in order that the operation may be understood. These relays are of the horizontal type and are mounted close together on a suitable base above the switch mechanism, the relative positions of the three relays being substantially as is shown immediately below the circuit diagram. Although each relay has a separate heel piece, there is nevertheless a certain amount of leakage of magnetic flux from the core of one relay to the cores of the adjacent relays, and with the line relay 100 in the center, as shown, this relay is in a position to influence and be influenced by the other relays to some extent. This effect is enhanced if the line relay is provided with a brass heel piece, which greatly increases the leakage of the magnetic flux. These three relays are wound in such directions that if the armature end of the line relay 100 is a north pole, for example, the armature end of the relays 101 and 102 will both be south poles. With this explanation the operations which take place when a line develops a short circuit high enough to operate the primary line switch and is extended to the first selector D will be understood. When the selector D is connected with, the line relay 100 is energized just enough, we will say, to cause armature 112 to engage contact spring 110, at which time the tension of spring 110 begins to resist the attraction of the armature and prevents further movement thereof for the time being. With armature 112 in engagement with spring 110, a circuit is completed for the release relay 101 which is energized and at armature 113 closes a circuit for the vertical magnet 105. Since the leakage flux produced by the energization of release relay 101 is in such a direction that it tends to build up the magnetism in the line relay 100, the line relay may now be sufficiently energized to completely attract its armature. At any rate, whether the line relay is completely energized at this time or not, the leakage flux due to the energization of the release relay 101 assists the energization of the line relay 100 instead of opposing it, and the establishment of a buzzer action between these two relays, such as would be apt to occur if the release relay were wound in the opposite direction, is prevented. Assuming then that the line relay 100 merely energizes sufficiently to close the three contact springs

together, when the vertical magnet operates the shaft is raised one step and off normal springs 122 and 123 are closed. This completes a circuit for relay 102, and also a circuit for relay 103. Relay 103, upon energizing, prepares the rotary magnet circuit in the usual manner. Relay 102 energizes an instant later and opens the vertical magnet circuit at armature 117 and closes the rotary magnet circuit at armature 118. The selector now operates to select an idle trunk line on the first level in the ordinary manner. Assuming that the trunk line terminating in bank contacts 150, 152, and 153, and comprising conductors 154, 155, and 156 is selected, the defective subscriber's line is extended to an operator's position, the operator's equipment in which the trunk line terminates being shown immediately above the secondary line switch S² in Fig. 2. The line relay which is bridged across this trunk line preferably has a weak adjustment and is accordingly energized, followed by the energization of the associated release relay which lights the lamp to attract the attention of the operator. It will be noticed that there is no provision made for grounding the release trunk conductor 155 in the ordinary course of events and it follows, therefore, that any connection which is extended to the operator's position by way of the trunk line in question will be locked up, since the lower winding of the release relay 101 will not be short circuited or de-energized. The operator may answer the call by throwing her listening key and in case there is a subscriber on the line who has called in on the first level by mistake, she can actuate the key K' which will ground the release trunk conductor 155 and place the circuits in such a condition that the subscriber can release the connection. Otherwise the operator will notify the switchboard attendant, who will proceed to trace back the call and ascertain the number of the line which is in trouble in order that the short circuit may be cleared. Although in the foregoing explanation a line having a high resistance short circuit has been mentioned, it will be apparent that a line having a high resistance ground on the negative side will be automatically extended to the operator in the same way.

The leakage flux between the cores of the line relay 100 and the relay 102 also has a pronounced effect on the latter relay in its ordinary operation, as will now be pointed out. Although the circuit of relay 102 is closed as soon as the switch shaft begins to rise, this relay is of very high resistance and impedance, as explained hereinbefore, and does not energize until the vertical movement is completed, at which time the line relay 100 comes to rest in energized position. At this time it is desirable that relay 102 should pull up instantly in order to

- start the rotary movement as soon as possible, and with the polarity of the relays as shown in the drawing, the line relay assists very much in securing this result. During 5 the time that operating impulses are being transmitted to the line relay it is energized only for brief intervals and never becomes fully saturated, consequently there is very little leakage flux to effect the relay 102. 10 When the line circuit is permanently closed, however, at the end of the transmission of a series of impulses, the magnetic flux in the line relay builds up rapidly until the relay becomes saturated and a considerable leakage 15 flux will now be produced which will effect the relay 102 in a proper manner to hasten its energization.

The scheme of so arranging the polarity of the line, release, and series relays so as to 20 assist in the operation of the switch can also be applied to an ordinary selector, such as the selector E, Fig. 3, in which switch it is availed of to improve the operation of the line relay 250 by causing the said relay to fall back more quickly when its circuit is 25 broken and to pull up more quickly when its circuit is closed. In this selector circuit the relays should be so wound that if the armature end of the line relay is the north pole, for example, the armature end of the release 30 relay 251 will also be a north pole, while the armature end of the series relay 252 will be a south pole. The relay polarities are indicated immediately below the circuit diagram of 35 the selector E, Fig. 3. Considering the operation of the switch in order to explain how the operation of the line relay 250 is improved, when the line relay is energized it closes a circuit for the release relay 251, and 40 the leakage flux produced by the energization of the latter relay will oppose the flux through the core of the line relay; consequently when the circuit of the line relay is broken it will deenergize more quickly than 45 would otherwise be the case. On the other hand, when the circuit of the line relay 250 is again closed after the first interruption the energization of release relay 251 is at a minimum, but series relay 252 is fully energized 50 and the polarity of this relay is such that the leakage flux produced by its energization tends to assist in the magnetization of the core of the line relay. It will be seen, therefore, that by properly arranging the windings of 55 the three relays mentioned, so as to produce proper polarities, the operation of the line relay can be considerably improved.

Having described my invention, what I consider to be new and desire to have protected by Letters Patent will be pointed out in the appended claims.

What I claim as my invention is:

1. In an automatic telephone system, two serially related automatic switches for connecting a calling and called line, a trunk 65 line extending between said switches including a release trunk conductor, means in the first switch for selecting said trunk line and for grounding said conductor when the trunk is connected with, means in the second 70 switch for grounding said conductor thereafter, and means in first switch responsive to the grounding of said conductor in the second switch for removing the ground in the first switch. 75

2. In a telephone system, a trunk line, a selector switch and means for operating it to connect with said trunk line, a self locking release relay in said selector switch, and means controlled over said trunk line for short circuiting the locking winding of said relay over a conductor of said trunk line to cause it to deenergize. 80

3. In a telephone system, a trunk line, a selector switch and means for operating it to connect with said trunk line, a self locking release relay in said selector switch, another switch in which said trunk line terminates, a line relay in the said other switch energized over the trunk line when the same is connected with, and means controlled by said line relay for grounding a conductor of said trunk line to short circuit the locking winding of said release relay to cause the said relay to deenergize. 90

4. In a telephone system, a group of trunk lines, a release trunk conductor in each trunk line, an automatic switch and means for operating it to connect with an idle trunk line, a release relay in said switch locked in energized position when the connection is established, and means controlled over the selected trunk line for grounding the release trunk conductor thereof to unlock said relay. 100

5. In a telephone system, a group of trunk lines, a release trunk conductor in each trunk line, an automatic switch and means for operating it to connect with an idle trunk line, a release trunk conductor incoming to said selector, means for connecting the said incoming release trunk conductor with the release trunk conductor of the selected trunk line when such trunk line is connected with, a release relay and a winding therefor supplying current to said incoming release trunk conductor, and means for connecting a current source to the release trunk conductor of the connected trunk line to short circuit said release relay and cause it to deenergize. 110

6. In a telephone system, a trunk line, a selector switch and means for operating it to connect with said trunk line, a quick acting line relay and a slow acting release relay controlling the operation of the switch, means for changing said release relay to a quick acting relay when the trunk is connected with, and a locking circuit for holding said release relay energized after its character is changed. 125

7. In a telephone system, a trunk line, a 130

selector switch and means for operating it to connect with said trunk line, a quick acting line relay and a slow acting release relay controlling the operation of said switch, a switching relay for completing the connection to said trunk line, means controlled by said switching relay for changing the release relay to a quick acting relay, a holding circuit for said switching relay completed over said trunk line after the same is connected with, and a locking circuit for maintaining said release relay energized until said holding circuit is established.

8. In a telephone system, a trunk line, a selector switch and means for operating it to connect with said trunk line, a quick acting line relay and a slow acting release relay controlling the operation of the switch, means for changing said release relay to a quick acting relay when the trunk is connected with, a locking circuit for holding said release relay energized after its character is changed, and means associated with the said trunk line for unlocking said release relay provided the trunk line is in operative condition.

9. In a telephone system, a trunk line, a selector switch and means for operating it to connect with said trunk line, a self locking release relay in said selector switch, and means for unlocking said relay contingent on said trunk line being in normal operative condition when connected with.

10. In a telephone system, a trunk line, a selector switch and means for operating it to connect with said trunk line, a self locking release relay in said selector switch, means for unlocking said relay only in case the said trunk line is in operative condition when connected with, and means for signalling an attendant if the relay is not unlocked.

11. In a telephone system, a subscriber's individual line switch, a trunk line, subscriber controlled means including a line relay for operating said switch to extend a connection over said trunk line, means for establishing a holding circuit over said trunk line to maintain said switch in operated position, means for disconnecting the line relay when the connection is extended, and a locking circuit for maintaining said line relay energized until said holding circuit is established.

12. In a telephone system, a subscriber's individual line switch, a trunk line, subscriber controlled means including a line relay for operating said switch to extend a connection over said trunk line, means for establishing a holding circuit over said trunk line to maintain said switch in operated position, means for disconnecting the line relay when the connection is extended, a locking circuit for maintaining said line relay energized until said holding circuit is established, and a connection between the said locking

circuit and holding circuit, whereby the said line relay is short circuited and deenergized when the holding circuit is established.

13. In an automatic telephone system, three serially related automatic switches for connecting a calling and called line, a release trunk conductor extending through all three of said switches after the connection is established, means for grounding said conductor in the first switch when the connection is extended to the second switch, means for grounding said conductor in the third switch when the connection is extended to the third switch, and means in the first switch responsive to the grounding of said conductor at the third switch for removing the ground at the first switch.

14. In a telephone system, three serially related switches for extending a calling telephone line, a line relay in the first switch, means in the first two switches responsive to the energization of said line relay for operating said switches to extend the calling line to said third switch, means for disconnecting said line relay when the first switch is operated, means in the said third switch for completing a holding circuit to maintain the first two switches in operated position, and a locking circuit for maintaining said line relay energized until the said holding circuit is established.

15. In a telephone system, three serially related switches for extending a calling telephone line, a line relay in the first switch, means in the first two switches responsive to the energization of said line relay for operating said switches to extend the calling line to said third switch, means for disconnecting said line relay when the first switch is operated, means in the said third switch for completing a holding circuit to maintain the first two switches in operated position, a locking circuit for maintaining said line relay energized until the said holding circuit is established, and a connection between the locking circuit and the holding circuit for short circuiting the locking winding of said line relay to deenergize the same.

16. In a telephone system, a selector switch and a repeater for connecting a calling and a called line, a rotary secondary line switch inserted between said selector switch and said repeater, a switching relay in said secondary switch for closing the talking conductors, a circuit for said switching relay maintained closed at the selector switch, means for closing said circuit at the repeater, and means for then opening said circuit at the said selector switch.

17. In a telephone system, a selector switch and a repeater for connecting a calling and a called line, a rotary secondary line switch inserted between said selector switch and said repeater, a switching relay in said secondary switch for closing the talking con-

ductors, a release trunk conductor extending through both of said switches to said repeater, a connection from said conductor to said switching relay to hold it energized, 5 means for grounding the said conductor in the selector switch including a release relay having a locking winding included in the ground connection, and means for grounding the said conductor in the said repeater, 10 whereby said release relay is short circuited and deenergized.

18. In an automatic telephone system, means for connecting a calling and called line including a repeater and outgoing trunk line and an automatic switch intervening between the calling line and said repeater, a manually operable key associated with said repeater, circuit arrangements cooperating with said key such that with the key in one 20 position the said switch cannot be released by the calling subscriber in case the trunk line is open, while with the key in the other position the calling subscriber can release the said switch, and means for making the repeater and trunk line busy after the switch 25 has been released.

19. In an automatic telephone system, means for connecting a calling and called line including in serial relation an automatic switch, a repeater, and an outgoing trunk line, means for preventing the calling subscriber from releasing the said switch in case the said trunk line is open, a signal, and means for operating said signal in case the calling subscriber attempts to release 30 said switch and is prevented from doing so.

20. In an automatic telephone system, a series of trunk lines and associated automatic switches for connecting a calling and called line, a controlling line relay for each switch bridged across the associated trunk line in series with the exchange battery, a condenser connected in bridge of each trunk line at the terminals of the associated line relay, and means for disconnecting each condenser and line relay after the associated 45 switch is operated.

21. In an automatic telephone system, serially related selector switches and a connector switch for connecting a calling and called line, interconnecting trunk lines, there being a trunk line terminating in each of said switches, a controlling line relay for each switch bridged across the associated 50 trunk line in series with the exchange battery, a condenser bridged across each trunk line at the terminals of the associated line relay, means for disconnecting the condenser and line relay from the trunk line at each 55 selector switch after such selector is operated, and means for disconnecting the condenser at the connector after it has been operated, the line relay at the connector being retained in bridge of the associated trunk line 60 to supply talking current to the calling line.

22. In an automatic telephone system; a selector switch having primary and secondary movement, a line circuit, a line relay responsive to momentary interruptions of the line circuit for causing the primary movement of said switch, and another relay responsive only to a prolonged closure of the line circuit following one or more momentary interruptions thereof for starting the secondary movement. 75

23. In an automatic telephone system, a selector switch having primary and secondary movement, a quick acting line relay and a slow acting release relay for controlling the operation and release of the switch, a relay for controlling the change over from primary to secondary movement, and a circuit for the change over relay closed by the line relay each time it is energized after the first deenergization during a series of impulses, the said change over relay having a winding of high resistance and impedance and being adjusted so that it will not operate until the line relay comes to rest in energized position after the series of impulses is finished. 85

24. In an automatic telephone system, a selector switch, a line relay for controlling the primary movement of said switch, and a second relay mounted adjacent said line relay and energized thereby for starting the secondary movement after the primary movement is completed, the said relays being so wound that the leakage flux from the line relay assists in energizing the said second relay. 95

25. In an automatic telephone system, a selector switch having primary and secondary movement, a line circuit, a line relay responsive to momentary interruptions of the line circuit for causing the primary movement of said switch, a second relay for starting the secondary movement mounted adjacent said line relay, a circuit for said second relay closed by said line relay after the first deenergization thereof, said second relay being responsive only to a prolonged energization of the said line relay following one or more deenergizations thereof, and the said relays being wound so that the leakage flux resulting from the prolonged energization of the line relay assists in the energization of the second relay and causes the latter to operate more rapidly. 105 110

26. In an automatic telephone system, a selector switch having a line relay, means for automatically extending a subscriber's line which is in trouble to the line relay of said selector, and circuit arrangements in the selector such that in case the line relay 120 is not fully energized the selector will operate automatically to extend the line which is in trouble to an operator's position. 125

27. In an automatic telephone system, a selector switch having primary and second- 130

ary movements and a controlling line relay, means responsive to a complete energization of said relay and momentary deenergizations thereof for causing the primary movement, 5 means for starting the secondary movement when the deenergizations cease, and circuit arrangements such that a partial energization of the said line relay will cause a definite primary movement followed automatically 10 by a secondary movement.

28. In an automatic telephone system, a selector switch having a primary operating magnet and a controlling line relay, a second relay for preparing a circuit for said operating magnet and for controlling the release of the switch, make before break contact springs on said line relay for controlling the primary magnet circuit and the circuit of 15 said second relay, and other circuit arrangements whereby the said line relay is prevented from permanently closing the circuit of the primary magnet in case said relay is only partially energized.

29. In an automatic telephone system, a selector switch having a primary operating magnet and a controlling line relay, a slow 25 acting release relay mounted adjacent said line relay, and make before break contact springs on said line relay for controlling the primary magnet circuit and the circuit of 30 said release relay, the said relays being wound so that when the release relay circuit is closed by the line relay the leakage flux produced by the energization of the release relay assists in the energization of the line relay.

30. In a telephone system, a selector switch, a quick acting line relay and a slow acting release relay for controlling said switch, said relays being mounted adjacent one another, and means for interrupting the circuit of the line relay to cause the operation 40 of the switch, the said relays being wound in such directions that the leakage flux produced by the energization of the release relay assists in deenergizing the line relay when its circuit is interrupted.

31. In an automatic telephone system, a selector switch and a line circuit extending 50 thereto, a line relay deenergized responsive to interruptions in the line circuit for controlling the primary movement of the switch, and a second relay for starting the secondary movement having a circuit which 55 is closed by the line relay at each deenergization thereof, said relays being mounted adjacent one another and being wound in such directions that the leakage flux produced by the energization of the said second 60 relay when the line relay is deenergized responsive to an interruption assists in energizing the line relay when the line circuit is closed following the interruption.

32. In a telephone system, a selector

switch and line extending thereto, a line 65 relay energized over the line circuit, a release relay energized by said line relay, means for interrupting the line circuit, a "change over" relay energized by the line 70 relay when the same deenergizes responsive to interruptions, the said relays being mounted adjacent one another, and said relays being wound in the proper directions so that the leakage flux produced by the 75 energization of the release relay assists in deenergizing the line relay when the line circuit is interrupted, while the leakage flux produced by the energization of the "change over" relay assists in energizing the line 80 relay when its circuit is closed.

33. In an automatic switch, two controlling relays, and magnetic cores for said relays each positioned within the magnetic field of the other so that the energization of one 85 relay will affect the operation of the other relay.

34. In an automatic switch, two controlling relays mounted adjacent one another and poled so that the leakage flux resulting from the energization of one relay assists in the 90 energization of the other.

35. In an automatic switch, three controlling relays mounted adjacent one another and poled so that the leakage flux resulting from the energization of the first relay will assist 95 in the energization of the second and so that the leakage flux resulting from the energization of the third will assist in the deenergization of the second.

36. In an automatic switch, a line relay, a release relay, and a "change over" relay, the line relay being mounted on the switch close to and between the other two relays and the said relays being so poled that the energization and deenergization of the line relay is assisted by the leakage flux resulting from the energization of the "change over" and release relays, respectively.

37. In an automatic switch, a line relay having a non-magnetic heel piece, and another controlling relay having a magnetic heel piece, said relays being mounted each within the magnetic field of the other so that the leakage flux produced by the energization of one relay affects the operation of the other relay.

38. In a telephone system, a trunk line leading to an operator's switchboard, automatic switches for extending a calling line to said trunk line, means for automatically 120 locking up the connection to prevent release by the calling subscriber, and means controlled by the operator for placing the release of the said switches under the control of the calling subscriber.

In witness whereof, I hereunto subscribe my name this 5th day of May, A. D., 1921.

CLARENCE E. LOMAX.
